UNITED STATES PATENT OFFICE.

OSCAR S. FIELD, OF NEW YORK, N. Y., ASSIGNOR TO HALL SWITCH & SIGNAL CO., A CORPORATION OF MAINE.

ALTERNATING-CURRENT RELAY.

1,272,410.

Specification of Letters Patent. Patented July 16, 1918.

Application filed January 3, 1917. Serial No. 140,439.

To all whom it may concern:

Be it known that I, OSCAR S. FIELD, a subject of the King of Great Britain, and a resident of the city of New York, county of 5 New York, and State of New York, have invented certain new and useful Improvements in Alternating-Current Relays, of which the following is a specification.

This invention relates to certain improved 10 means of construction of alternating current relays, applying more specifically to that type which is known as the two phase induction motor relay and which employs a hollow non-magnetic cup rotor in its operation.

One object of this invention is to provide 15 a relay of the above type which will have its contacts and contact fingers fully exposed and easy of access and inspection without interfering with the operating parts of the 20 relay.

Another object of the invention is to provide 25 a novel construction and arrangement of parts which will allow inspection of the operating parts at all times.

Various other objects and novel features 30 will be more specifically described in the accompanying description and claimed in the appended claims.

Referring to drawings, in Figure 1 I show 35 a transverse section through the relay.

Fig. 2 is a front elevation of the same.

Fig. 3 is an elevation with the front part 40 of the relay removed, showing the windings and cup rotor.

Fig. 4 is a back elevation of the front part 45 of the relay showing the operating pinion and gear segment.

Referring to Fig. 1, I show a front member 1 to which is attached a case 2 having an 50 internal annular support 3 formed therein, upon which is mounted a soft iron laminated ring shaped core 4. About the core 4 is a multipolar laminated field structure 5 which is provided with operating windings 6 and 7 55 so angularly disposed that when they are energized by means of two phase alternating current it will create a moving flux field between the pole pieces 8 and the core 4 in the well known manner of an induction motor.

In the annular space formed between the core 4 and the pole pieces 8 of the laminated field structure 5, a non-magnetic cup rotor 9 is 60 mounted on a spindle 10 journaled in bearings 11 and 12, the cup 9 being freely mounted on the spindle 10 and clamped between

friction washers 13 and 14 by means of a compression spring 15 acting between the retainer ring 16 and the friction washer 14. It will therefore be seen, that the cup 9 will be free to rotate in the annular space 65 between the core 4 and pole pieces 8 and will be free to slip upon the shaft 10 upon any undue torque being placed upon the cup. On the front end of the shaft 10 a pinion 17 is rigidly mounted, and gear segment 18 70 mounted to swing on a spindle 19 meshes with the pinion 17, being counter-weighted at 59 so that it will normally assume the position shown in Fig. 4 with the projection 29 resting against the inside wall 21 of member 1.

Gear segment 18 is provided with a crank pin 22 so arranged that upon the movement of gear segment 18 by means of rotation of pinion 17 acting against the counterweight 75 59 which is carried by extension 29 rigidly attached to gear-segment 18, the connecting link 23 will be forced downward. The link 23 is connected by means of a pin 24 to a lever arm 25 which operates about a center 80 26 and attached to the lever arm 25 is the contact finger carrying bar 27 made of insulating material, on the underside of which are mounted contact fingers 28.

The front member 1 is provided with an 85 opening 29 in which an insulating panel 30 is mounted. This panel is provided with a series of front contacts and binding posts 31 and back contacts and binding posts 32, with which the contact fingers 28 are adapted to co-act. The panel also carries a series of binding posts 33 from which flexible leads 34 pass to the contact fingers 28.

In a recess 35 on the underside of member 1 is a gasket 36, and a cover 48 made 95 of glass or other transparent material, adapted to incase the contacts 31 and 32 and the co-acting contact fingers 28 being clamped against the gasket 36 by means of rod 37 and clamping nut 38. The front 100 member 1 is also provided with an opening 39 in the front part thereof, above the insulating panel 30, this opening being closed by means of a cover glass 40 retained in place by means of clamping ring 41 thereby 105 allowing free inspection of the mechanism at all times.

Front member 1 is provided with extension 42 which forms front supports for the relay, the back case 2 being supplied with 110

an extension 43 which acts as the back support. Back case 2 is further supplied with lugs 44 in order that the relay may be hung upon the wall when necessary.

5 The leads of the windings 6 and 7 are brought out to terminals 45 and 46, which are mounted in suitable insulating inserts 47, which further act to retain the field laminations 5 in place.

10 Referring to the various drawings, the operation of the relay is as follows:—

The winding 6 is continuously energized from a transformer or other suitable source of a given frequency.

15 Winding 7 is energized from a controlled source of alternating current of the same frequency as the energy in winding 6 but angularly displaced as to phase, which will thereby, when winding 7 is energized, create 20 a rotating flux field which will act upon the cup rotor 9 to cause the rotation of the same.

The cup rotor will rotate the spindle 10 and its pinion 17 which engages with gear 25 segment 18, and will thereby force gear segment 18 over against the action of counterweight 59, force connecting link 23 downward and rotate lever 25 about the pivot 26, thereby causing the contact fingers 28 to 30 be raised until they engage with the front contacts 31. At this time the counterweight 59 will strike the top of member 1 at 57, thereby preventing further motion, the cup 9 slipping on spindle 10 in order to absorb 35 its momentum. If the winding 7 of the relay is now deenergized the counterweight 59 will force the gear segment 18 backward thereby rotating cup 9 backward and also moving link 23 upward, and causing contacts 28 to move downward until they break 40 their connection with contacts 31 and make connection with contacts 32 as shown in Figs. 1 and 2.

Thus it will be seen that by keeping 45 one set of windings continuously energized from a local source of a certain frequency, and by intermittently energizing the other set of windings from a source of the same frequency but angularly displaced in phase, 50 the relay may be caused to open and close its front and back contacts at will, and thereby control local circuits to any desired extent.

While I have described and shown one 55 specific form of my invention, I do not wish to be limited to this specific means of construction, as it is obvious that a variety of different modes of construction may be employed without departing from the spirit 60 of the invention.

Having described my invention, what I claim as new and desire to secure by Letters Patent is:

1. In combination in a relay, a back mem-

ber containing an alternating current motor, a front member, an opening in the upper part of said front member to allow inspection of the operating mechanism, a cover for said opening, a forward extension below the opening in said front member adapted to carry an insulating panel, an insulating panel, contacts carried by said insulating panel, a contact finger bar carried by said front member, contact fingers carried by said bar in operative relation to said contacts, means for transmitting motion from the motor to the contact finger carrying bar to operate the contact fingers, and a cover adapted to inclose said contacts and contact fingers.

2. In combination in a relay, a back member containing an alternating current motor, a pinion on the shaft of said motor, a front member, a gear segment pivoted in said front member and adapted to be operated by said pinion, a counterweight on said gear segment to return the same upon deenergization of the operating mechanism, an opening in the upper part of said front member to allow inspection of the operating mechanism, a cover glass for said opening, a forward extension below the opening in said front member adapted to carry an insulating panel, an insulating panel, contacts carried by said insulating panel, a contact finger carrying bar carried by said front member, contacts carried by said bar in operative relation to said contacts, means for transmitting motion from said gear segment to said contact finger carrying bar to operate the contact fingers, and a cover adapted to inclose the contacts and contact fingers and engage with said forward extension.

3. In combination in a relay, a back member adapted to carry an inner magnetic core, an outer stator inclosed in said member, operating windings on said stator, a shaft, a nonmagnetic rotor on said shaft in operative relation to said inner core and outer stator, a friction drive between said rotor and said shaft, a pinion on said shaft, a front member, a gear segment pivoted in said front member and adapted to be operated by said pinion, a counterweight on said gear segment to return the same upon deenergization of the operating mechanism, an opening in the upper part of said front member to allow inspection of the operating mechanism, a cover glass for said opening, a forward extension below the opening in said front member adapted to carry an insulating panel, an insulating panel, contacts carried by said insulating panel, a contact finger carrying bar carried by said front member, contacts carried by said bar in operative relation to said contacts, means for transmitting motion from said gear segment to said contact finger carrying bar to operate the

- contact fingers, and a cover adapted to inclose the contacts and contact fingers and engage with said forward extension.
4. In combination in a relay, a back member adapted to carry an inner magnetic core, an outer stator inclosed in said member, operating windings on said stator, a shaft, a nonmagnetic rotor on said shaft in operative relation to said inner core and outer stator, a friction drive between said rotor and said shaft, a front member, an opening in the upper part of said front member to allow inspection of the operating mechanism, a cover for said opening, a forward extension below the opening in said front member adapted to carry an insulating panel, an insulating panel, contacts carried by said insulating panel, a contact finger bar carried by said front member, contact fingers carried by said bar in operative relation to said contacts, means for transmitting motion from the motor to the contact finger carrying bar to operate the contact fingers, and a cover adapted to inclose said contacts and contact fingers.
5. In combination in a relay, a back member adapted to carry an inner magnetic core, and an outer stator inclosed in said member, operating windings on said stator, insulating panels in said back member adapted to carry binding posts for the operating windings and to retain said outer stator in place, a shaft, a nonmagnetic rotor on said shaft in operative relation to said inner core and outer stator, a friction drive between said rotor and said shaft, a front member, a gear segment pivoted in said front member and adapted to be operated by said pinion, a counterweight on said gear segment to return the same upon deenergization of the operating mechanism, an opening in the upper part of said front member to allow inspection of the operating mechanism, a cover glass for said opening, a forward ex-
- tension below the opening in said front member adapted to carry an insulating panel, an insulating panel, contacts carried by said insulating panel, a contact finger carrying bar carried by said front member, contacts carried by said bar in operative relation to said contacts, means for transmitting motion from said gear segment to said contact finger carrying bar to operate the contact fingers, and a cover adapted to inclose the contacts and contact fingers and engage with said forward extension.
6. In combination in a relay, a back member adapted to carry an inner magnetic core, lugs formed on said back member for suspending the relay, an outer stator inclosed in said back member, operating windings on said stator, insulating panels in said back member adapted to carry binding posts for the operating windings and to retain said outer stator in place, a shaft, a nonmagnetic rotor on said shaft in operative relation to said inner core and outer stator, a friction drive between said rotor and said shaft, a front member, an opening in the upper part of said front member to allow inspection of the operating mechanism, a cover for said opening, a forward extension below the opening in said front member adapted to carry an insulating panel, an insulating panel, contacts carried by said insulating panel, a contact finger bar carried by said front member, contact fingers carried by said bar in operative relation to said contacts, means for transmitting motion from the motor to the contact finger carrying bar to operate the contact fingers, extensions formed on the front and back members to form supporting feet, and a cover adapted to inclose said contacts and contact fingers.
- In testimony whereof, I have signed my name to this specification.

OSCAR S. FIELD.
